UNITED STATES PATENT OFFICE

ROBERT T. PLATE, OF DETROIT, MICHIGAN

HAIR CURLER

Application filed June 6, 1932. Serial No. 615,601.

The present invention relates to a novel device for curling and waving hair and particularly refers to that type of curler wherein means is provided for receiving the end of a lock of hair in a manner whereby the hair may be wound around the same and secured thereon in a manner to cause the same to wave when again unwound from the curler.

The primary object of the present invention is to provide a retaining member of semi-cylindrical form having means by which it may be conveniently assembled on a flexible wire to coat with a sleeve-like member on said wire in retaining the end of a strand of hair may be wound around the same. In order to place the hair between the retaining member and the sleeve member in the present type of curler, it is necessary to pivot the retaining member and the sleeve member relative to each other and the present invention attains this required movement by a flexing of the wire in a manner which avoids all possibility of strands of hair becoming caught between pivotally movable parts and thereby 25 damaging the hair and causing pain to the user.

With the above and other ends in view the invention consist in matters hereinafter set forth and more particularly pointed out in 30 the appended claims, reference being had to the accompanying drawing, in which

Figure 1 is a side elevation of the present curler in the normal position;

Fig. 2 is a side elevation illustrating the 35 parts in a position to receive the hair;

Fig. 3 is a side elevation illustrating the manner in which the ends of the wire are bent to hold the parts around the hair;

Fig. 4 is an end elevation, and

Fig. 5 is a plan view of the blank from 40 which the semi-cylindrical retaining member is formed.

Like characters of reference are employed throughout to designate corresponding parts.

The numeral 1 indicates an elongated flexible wire member, preferably having a coating of protective material such as fabric or rubber. Immovably secured on the wire 1 is a 45 sleeve like member 2 which forms an enlargement thereon, the sleeve member being of

metal, composition or of wood with an exterior finish or coating that gives the same a pleasing appearance. Secured to the wire 1, adjacent one end of the sleeve 2 is a semi-cylindrical retaining member 3 which is 55 formed with a radius slightly larger than the outside diameter of the sleeve 2 so that said sleeve may project into said retaining member.

The present invention has special reference to the particular formation of the retaining member which, as illustrated in Fig. 5 is formed of a substantially rectangular sheet metal blank 3' having an arm 4 extending outwardly in the direction of the length of said blank. On the outermost end of the arm 4 are formed fingers 5 with their ends cut on a bias as illustrated at 6.

In assembling the present device the blank 3' is bent to a semi-cylindrical form and the arm 4 is bent inwardly in a radial direction. The fingers 5 are then bent around the wire 1 adjacent the end of the sleeve 2. In this manner the radially extending arm 4 on the semi-cylindrical member 3 supports a loop formed 75 by the fingers 5 around the wire concentric with the sleeve 2 which in turn holds the retaining member concentric with the sleeve.

In using the present device the sleeve 2 and retaining member 3 are moved apart as illustrated in Fig. 2, it being noted that this movement is permitted by a flexing of the wire between the fingers 5 and the end of the sleeve 2 as indicated at 7. When in the position illustrated in Fig. 2 the end of a lock of hair may be interposed between the sleeve 2 and retaining member 3 and the latter again be moved to the position illustrated in Fig. 1 to hold the hair while it is being wound around the outside of the sleeve and retaining member by rotating the device. After the hair is wound around the device the wire members may be bent as illustrated in Fig. 3 to prevent the hair from unwinding of its own accord.

Although a specific embodiment of the present invention has been illustrated and described it is to be understood that various changes may be made within the scope of the appended claims without departing from the 100

spirit of the invention, and such changes are contemplated.

What I claim is:—

1. A hair curler comprising a flexible wire, a concentric enlargement on said wire, and a semi-cylindrical retaining member adapted to receive said enlargement, said retaining member being secured to said wire adjacent the end of said enlargement whereby movement of said retaining member relative to said enlargement is accomplished by bending said wire.
2. A hair curler comprising a flexible wire having an enlargement thereon, a retaining member, and an arm on said retaining member having means engaging said wire adjacent the end of said enlargement.
3. A hair curler comprising an elongated flexible wire, a cylindrical enlargement on said wire, a semi-cylindrical retaining member, and a radially extending arm on said retaining member adapted to be secured to said wire adjacent the end of said enlargement.
4. A hair curler comprising an elongated flexible wire, a cylindrical enlargement on said wire, a semi-cylindrical retaining member, a radially extending arm on said retaining member, and fingers on said arm adapted to be looped around said wire adjacent the end of said enlargement.
5. A hair curler comprising a flexible wire, a cylindrical sleeve secured on said wire intermediate its ends, a semi-cylindrical retaining member, a radially extending arm formed on the end of said sleeve, and fingers on said arm engaging said wire adjacent the end of said sleeve.

In testimony whereof I affix my signature.

ROBERT T. PLÄTE.
